COMBINED HOLDER FOR A CAN AND SUPPORT FOR A SPONGE

Constance Carroll, 154 W. 73rd St., New York, N.Y.

Filed Nov. 18, 1963, Ser. No. 77,466

Term of patent 14 years

(Cl. D44—29)

FIG. 1 is a side elevational view of a combined holder for a can and support for a sponge showing my new design.

FIG. 2 is a similar view showing the base of FIG. 1, drawn to an enlarged scale.

FIG. 3 is a top plan view of the base shown in FIG. 2.

FIG. 4 is a bottom plan view of the base shown in FIG. 2.

FIG. 5 is a sectional view taken along line 5—5 of FIG. 3.

FIG. 6 is a fragmentary sectional view of the base shown in FIG. 3, with the clamping arm secured in place.

FIG. 7 is a side elevational view of the clamping arm as seen in FIG. 6.

FIG. 8 is a fragmentary front view of the lower part of the clamping arm.

FIG. 9 is a rear view of the clamping arm of FIG. 7. The portions shown in broken lines are for illustrative purposes only.

I claim:

The ornamental design for a combined holder for a can and support for a sponge, substantially as shown and described.
